LOOM HARNESS STOP MOTION

Tillmon J. Sanders, Utica, N. Y.

Application February 26, 1943, Serial No. 477,271

2 Claims. (Cl. 139—337)

My invention relates to looms, and has among its objects and advantages the provision of an improved stop motion operating in conjunction with the loom harness to be set in operation upon breaking of a harness strap.

In the accompanying drawings:

Figure 1 is a diagrammatic view illustrating my invention in association with a loom harness and the usual drop wires.

Figure 2 is a sectional detail view of a harness actuated plunger means.

Figure 3 is an elevational view of the structure of Figure 2, but illustrating the broken harness engaged therewith.

Figure 4 is a top view of a harness engaging bar.

Figure 5 is a sectional and diagrammatic view illustrating a lever means actuated by the structure of Figures 2 and 3 and arranged for coaction with the stop motion bar of the loom.

Figure 6 is a top view of the lever structure of Figure 5, and

Figure 7 is a perspective view of a part of the lever structure of Figures 5 and 6.

In the embodiment of the invention selected for illustration, Figure 1 illustrates a loom harness 10 and straps 12 for actuating the harness. The usual drop wires are indicated at 14 in association with an oscillating stop motion bar 16.

Underneath the harness 10 is mounted a bar lever 18 of U-shaped contour and having its ends pivotally connected at 20 with a head 22 fixed to a bar or post 24 which may be attached to the loom frame structure (not shown).

In Figures 2 and 3 a plunger 26 is located underneath the bar lever 18 to be thrust downwardly when the harness drops onto the bar lever. This bar lever is provided with a flange 28 arranged to constitute a pusher element for the plunger 26. The plunger is slidably guided in a tubular housing 30 adjustably mounted in an opening 32 in a projection 34 on the post 24. A flexible wire 36 is attached to the head 38 on the plunger 26, which wire is slidably guided in a coiled wire tube 40, such as a Bowden wire.

A plug 42 is threaded into the lower end of the housing 30 and constitutes an abutment for one end of a compression spring 44 engaging the head 38, in addition to serving as a support for the tube 40, the latter being made secure by a set screw 46. Precise adjustment of the plunger 26 with respect to the bar lever 18 is attained through the adjustable association of the housing 30 with the projection 34, a set screw 46 being provided for fixedly relating the housing to the

projection. The tension of the spring 44 is such as to normally hold the bar lever 18 in the position of Figure 2, but the spring yields when the harness 12 drops upon the bar, as in Figure 3, to impart endwise movement to the plunger 26 and its attached wire 36.

The other end of the wire 36 is inserted in an axial bore in one end of a link 48 slidably guided by a tubular housing 50. This housing is adjustably connected with a bracket 52, which bracket is attached to a support 54, which may comprise the stop motion stand of the loom. A set screw 56 is threaded into the bracket 52 for engagement with the housing 50 to fixedly relate the latter to the bracket.

A flange 58 is threaded on the link 48 and serves as a support for one end of a compression spring 60 having its other end abutting the top end of the housing 50 to normally hold the link 48 in the position shown. The tube 40 is secured in a plug 62 threaded into the lower end of the housing 50. A set screw 64 is threaded into the plug 62 for engagement with the tube 40.

To the upper end of the link 48 is pivotally connected one end of a lever 66 pivotally connected intermediate its ends, as at 68, with an upstanding arm 70 on the bracket 52. To the other end of the lever 68 is attached a blade 72 in the nature of a drop wire. This blade extends downwardly between certain of the drop wires 14 arranged to fall into the path of the stop motion bar 16. Normally the blade 72 is spaced upwardly from the bar 16 and is projected into the path of the bar only when a harness drops onto the bar lever 18. The blade 72 includes a slot 76 providing accommodation for the bar 78 associated with the drop wires 14.

Harness straps are frequently broken. My invention operates to stop the loom upon breaking of a harness strap. The device is easily attached to the loom and operates sufficiently as an adjunct to the usual drop wire stop motion.

Without further elaboration, the foregoing will so fully explain my invention, that others may, by applying current knowledge, readily adapt the same for use under various conditions of service.

I claim:

1. A stop motion device for use with a loom having a harness, and a stop motion member, comprising a first pivoted lever mounted beneath the harness to be engaged and pivoted thereby when the harness breaks, a spring pressed plunger slidably mounted beneath and engaging the first lever and adapted to normally hold the same in an inoperative position, a blade movable to a posi-

tion in the path of the stop motion member of the loom, a second pivoted lever carrying the blade, a spring pressed link connected with the second lever to normally hold the lever and blade in operative position with respect to the stop motion member, and a flexible wire connection between the plunger and the link to actuate the link, the second lever and the blade to move the blade into the path of the stop motion member when the first membered lever is engaged and moved by a broken harness to actuate the plunger and flexible wire.

2. A stop motion device for use with a loom having a harness, and a stop motion member, comprising a flanged bar lever pivoted beneath the harness to be engaged thereby when the harness breaks, a spring pressed adjustable

5 plunger slidably mounted beneath and engaging the flange of the bar lever to normally hold the same in an inoperative position, a blade movable to a position in the path of the stop motion member of the loom, a pivoted lever carrying the blade, a spring pressed link connected with the pivoted lever to normally hold the lever and blade in inoperative position with respect to the stop motion member, a flexible wire connection between the plunger and the link to actuate the lever, the pivoted lever, and the blade to move the blade into the path of the stop motion member when the bar lever is engaged and moved by a broken harness to actuate the plunger and flexible wire, and means for adjusting the action of said link.

TILLMON J. SANDERS.
